UNITED STATES PATENT OFFICE.

WALLACE C. LYON, OF HYATTSVILLE, MARYLAND.

SKYLIGHT CONSTRUCTION.

1,192,654.

Specification of Letters Patent. Patented July 25, 1916.

Application filed April 14, 1916. Serial No. 91,251.

To all whom it may concern:

Be it known that I, WALLACE C. LYON, a citizen of the United States, residing at Hyattsville, in the county of Prince Georges and State of Maryland, have invented certain new and useful Improvements in Skylight Constructions; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in construction of skylights and the object in view is to produce a novel cushioning means, consisting of a helix or coil of flexible metal as a bedding or support for glass panels, so that parts of the coil may yield to conform to any irregularities there might be in the under surface of the glass panels of the skylight.

Another and an important feature of the invention is in the provision of means for sealing the glass panels upon their outer faces by the provision of sealing members connected with the astragal caps, which serve to clamp and hold the sealing members against the outer face of the panels and causing the knife edges of the sealing members to conform to and produce line contact with the surfaces thereof.

The invention comprises various other details of construction, combinations and arrangements of parts which will be herein-after fully described, shown in the accompanying drawings, and then specifically defined in the appended claims.

My invention is illustrated in the accompanying drawings, in which:

Figure 1 is a small scale top plan view of a section of a skylight made in accordance with my invention. Fig. 2 is a sectional view on line R—R of Fig. 1, showing a section at the ridge. Fig. 3 is a large scale top plan view, a portion being broken away to illustrate the metallic coils forming bearings for the glass. Fig. 4 is a sectional view on line C—C of Fig. 1, showing a section through a cross gutter. Fig. 5 is a sectional view on line E—E of Fig. 1, showing a section through the eaves gutter. Fig. 6 is a sectional view through an astragal on line A—A of Fig. 1. Fig. 7 is an enlarged de-

tail sectional view through a portion of an astragal cap and sealing member and illustrating a portion of a panel of glass against which the sealing member contacts, and Fig. 8 is a sectional view of sealing member F² having a vertical knife-edged wall in line contact with the glass panel.

Reference now being had to the details of the drawings, it will be noted upon reference to Fig. 6 of the drawings, showing a cross sectional view through an astragal of a skylight construction, a sheet A, made of any suitable material, is bent as shown to form trough-shaped flanges B and C. A longitudinal central portion of the sheet is bent as shown in Fig. 6 and is apertured for the reception of the T-head threaded bolts D which are arranged at intervals along the ridge and astragal caps. Said sheet A is held to the upright portion of the core bars B' by means of the rivets G, said core bars being fastened by rivets G⁴ to the clips G² which in turn engage the purlins G³.

E designate astragal caps which are apertured for the reception of the bolts D, and D' designate nuts fitted upon the bolts D and are adapted to bear against the horizontally disposed portion of the caps E. The opposite edges of the astragal caps E are bent as at D², shown clearly in Figs. 6 and 7 of the drawings, and F designate sealing members, which are of the usual construction of "cames" of standard manufacture and made of yielding metal, such as lead, the lower edges of which are sharp and adapted to rest upon and conform to any unevenness in the upper surface of the panels of glass, designated by letter F', when the nuts D', shown in the drawings, are tightened upon the bolts, causing pressure to be applied to the sealing members through the caps and thereby make a tight or sealed joint intermediate the sealing members and the upper surface of the glass.

Helices or coils of wire of lead, lead alloy or other suitable yielding metal, designated by letter T', rest in the trough flanges B and form a yielding bedding or support for the panels of glass, which rest thereon, the top of the coils being sufficiently high above the edge of the trough-shaped flanges to permit of the deflection of the glass panels without the same coming in contact with the edges of the said flanges the degree of yielding qualities of the coils being determined by the proximity of the convolutions

thereof to one another, it being understood that the nearer the convolutions are to one another the greater will be the sustaining strength of the helix to resist compression and diminishing correspondingly the yielding of the same under pressure which might come upon the coils, or by varying the degree of hardness of the lead alloy, if used in lieu of pure lead, or by both. Said coils 10 form means whereby when the nuts D' are tightened upon the bolts, the panels of glass are pressed down upon the coils of lead or other material and, by reason of the yielding quality of the helix the latter may 15 be made to conform to any irregularities there might be in the under surface of the glass and without, of course, forming any sealed joint underneath the panel, the purpose of the present invention being to seal 20 the water from the outer or upper surface of the panel instead of upon the under surface thereof which has heretofore been a common practice in skylight construction.

Referring to Fig. 4 of the drawings will 25 be seen a cross gutter designated by letter K, which is bent to form two gutters, designated respectively by letters K and L, while a portion of the sheet is bent upon itself at N and thence at right angles, having 30 a portion O forming a support for the glass panel Q, which part O rests upon a lead coil Q', while the edge of an adjacent panel of glass Q² rests upon the angled edge L' and also rests upon the coil. In said Figs. 4 35 and 6 of the drawings, it will be noted that any water which might run through the space intervening between the lower end of the glass panel Q and the portion of the gutter K which is bent upon itself, and 40 which might rise up the inclined surface of the portion O would be caught in the gutter K and any moisture which might back up underneath the bent portion N, which extends over the upper surface of the glass 45 panel Q², would be caught in the gutter L and conveyed therefrom into the gutter C, shown in Fig. 6 of the drawings.

In Fig. 4 of the drawings, the astragal cap L³ is held by means of the T-bolts D 50 with the nuts D' thereon in the same manner as shown in Fig. 6, forming means whereby the cap L³ may hold the cames L⁶ against the upper surfaces of the glass panels Q and Q², forming a tight joint intermediate the 55 same and which in turn will cause the panels to press upon the wire coils, making the latter conform to the irregularities in the under surface of the panels while the sharp edges of the cames conform to any irregularities upon the upper surface of the glass 60 panels forming sealed joints.

In Fig. 5 of the drawings, two gutters, designated respectively by letters J and J', are formed as shown with the sheet J' bent 65 upon itself, forming a trough J² which sup-

ports the lead coil J³ upon which the glass J⁴ rests, the edge of the sheet forming the gutter J² being bent over the upper end of the sheet J. The two sheets J and J' are fastened together by rivets J⁵ and the sheet J' is bent to form a gutter J⁶ and the inner edge of the sheet J is bent over the upwardly extending edge J⁷, as shown clearly in the drawings. The sheet J, which is bent to form the lower gutter J⁸, has a drip opening J⁹, while the gutter J has a similar opening J¹⁰ and through which any water which might accumulate in the gutter J⁶ may run into the gutter J⁸ and thence out through the exit opening J⁹. The inner edges of the two 80 sheets J and J' rest upon the skylight curb support J¹¹ and which also supports the bracket J¹².

In Fig. 2 of the drawings is illustrated a 85 sectional view through the ridge of the skylight and in which the ridge cap is designated by letter M, which is bent in a similar manner as shown in Fig. 6 with its opposite edges bent as illustrated and each resting upon a sealing member M'. R' is a ridge 90 gutter for the support of the glass panels bent to form two gutters R, while the central portion is apertured for the reception of a T-bolt R² which passes through an 95 aperture in the cap M and is engaged by a nut R³. The panels of glass T, shown in Fig. 2 of the drawings, rest upon the lead coils T' which are adapted, when the nuts R³ are tightened, to cause the lower sharp 100 edges of the sealing members M', under pressure, to yield to conform to any irregularities in the upper surfaces of the glass, thus making tight joints between the same and the glass.

From the foregoing, it will be noted that, 105 by the provision of a skylight construction made in accordance with my invention, I provide means whereby the panels of glass are sealed upon their upper or outer faces by reason of the sealing members being held 110 under pressure with their sharp edges against the upper faces of the glass panels and parts of the edges of the sealing members conforming to any irregularities there might be in the surface of the glass. In the 115 event of water from any cause running down through the spaces intermediate the upper ends of the glass panels and the ridge gutter upon which the latter rests, it will be caught by the gutters R and R' and conveyed away thereby to main gutters C, 120 shown clearly in Fig. 6. It will also be noted that, by the provision of the coils of lead or other suitable material, a support or bedding is afforded for the panels of glass 125 upon the coils which will, under pressure, conform to any irregularities upon the under surface of the glass.

What I claim to be new is:—

1. In a roof construction, and in combina- 130

tion with a panel thereof, a cushioning member for supporting said panel, said member consisting of a helix formed of a strip or wire composed of a yielding material, upon the upper surface of the convolutions of which the lower face of said panel rests.

2. In a skylight construction and in combination with panels thereof, cushioning members for supporting said panels, each 10 of said members consisting of a helix formed of a strip or wire composed of yielding material, upon the upper surfaces of the convolutions of which the lower face of said panels rest, and water tight sealing members, making a line contact with the upper 15 surface of said panels and being water tightly connected to covering caps or crown pieces of the skylight astragal.

3. In a skylight, an astragal having 20 trough-shaped outstanding wings or flanges,

cushioning members removably and replaceably supported upon the trough of said wings or flanges, each cushioning member consisting of a helix formed of a strip or wire composed of a yielding material, and 25 glass panels having their under surfaces resting upon the top surface of the convolutions of said helix.

4. The combination with an astragal cap having a laterally flanged edge of a sealing 30 strip having a channel in its top surface adapted to receive said flanged edge and one or both walls of the channel being folded down behind said flange.

In testimony whereof I hereunto affix my 35 signature in presence of two witnesses.

WALLACE C. LYON.
